UNITED STATES PATENT OFFICE.

ROY F. BANCROFT, OF TROPICO, CALIFORNIA.

EXPRESSION AND FEED CONTROL FOR PIANO-PLAYERS, &c.

No. 899,094.

Specification of Letters Patent.

Patented Sept. 22, 1908.

Application filed July 31, 1903. Serial No. 323,628.

To all whom it may concern:

Be it known that I, ROY F. BANCROFT, a citizen of the United States, residing at Tropico, in the county of Los Angeles and State of California, have invented a new and useful Expression and Feed Control for Piano-Players, &c., of which the following is a specification.

One object of this invention is to provide for controlling the expression or variation of force in piano players, by means acting automatically under the control of the music sheet. In piano players it is usual to provide a manually operated expression lever, 10 by manipulation of which the person operating the instrument can vary the force of playing at will. Marks are also sometimes arranged on the controlling sheet to indicate the proper force for playing during the progress of the piece. Perfect rendering of the piece would require that the person follow exactly the directions as given by the marks. My invention provides for such perfect rendering of the music without depending on 25 personal attention.

Another object of the invention is to provide for automatic control by the music sheet, of the speed at which the sheet is moved, and thereby of the speed or tempo 30 of different parts of the piece. Means for manual control of the speed and for indicating to the operator the proper rate of speed are now provided in some cases, and my invention provides for effecting such variation 35 of speed without personal attention.

Another object of the invention is to aid or accentuate the expression control by the coöperative action of the speed control, as hereinafter set forth.

40 In the accompanying drawings Figure 1 is a front elevation of a piano player showing in dotted lines the general location and arrangement of my controlling devices. Fig. 2 is a vertical section on the line x^2-x^2 in Fig. 45 1. Fig. 3 is a front elevation, somewhat diagrammatic, of the controlling devices. Fig. 4 is a plan of a fragment of the controlling sheet.

Referring to Fig. 1 and Fig. 2 the piano 50 player is assumed to comprise the usual elements including the case 1, pedals 2, tracker board 3, the rolls 4 and driving mechanism therefor, operated by the motors 5, supplied through pipe 6 from the reservoir 7.

55 8 designates the action or key pneumatics which are connected to tubes 9, leading to

the perforations 10 in the tracker board, said key pneumatics being connected by the pipe 11, with the reservoir 7, said pipe including a valve 12 to regulate the passage of air from the reservoir to the key pneumatics, or in case a suction pipe is used to regulate the suction of air from the key pneumatics.

50 The invention is assumed to be applied in connection with the suction system and will be so described herein, but it will be understood that it is equally applicable to a pressure system of operation.

The invention comprises means for automatically controlling the valve 12 to regulate 70 the force of playing, this action being subjected to control by the music sheet itself. For this purpose a pneumatic 13, herein shown as a bellows pneumatic is operatively connected to valve 12 as by links 14 connecting a movable member 15 of the bellows pneumatic, with the spindle 16 of the valve and said pneumatic is connected to a conduit or conduits controlled by the music sheet. It is preferable to provide for gradation of 80 the modifying action, so as to give a plurality of degrees of expression. For this purpose the bellows pneumatic 13 is provided with a plurality of bellows elements which may be mounted side by side and separated by walls 85 18 mechanically connected to one another and to end walls 15, 20 by yielding walls 19. The end wall 20 at one end of the bellows is fixed so that on inflation or deflation of any one of the bellows elements the outer wall 90 will be moved a certain distance, and on inflation or deflation of a plurality of such elements the said outer wall and the valves connected thereto will be moved a correspondingly greater distance. The several bellows 95 elements are connected by pipes 21 with special perforations 22 in the tracker board 3, each pipe 21 extending into a passage 17 in the walls 20 or 18 which open into the bellows chamber between said wall and the next 100 outer wall. The outer end of said passage 17 connects by duct 48 and box 49 with a pipe 23 leading to the reservoir 7. 24 designates a spring for expanding or inflating the bellows. The usual expression lever 25 may also be used, connected by means 26 to a valve 27, to control suction of air from the action. When this manual control is in operation it is desirable that the automatic control should be thrown off so that the manual 110 and automatic control do not interfere. For this purpose valve 27 is connected to a

valve member 28 which when the valve 27 is in operative position, cuts off communication from reservoir pipe 23 to the pneumatic 13, thus allowing valve 12 to move to full open position and putting port 29 under control of the valve 27. When the manual expression lever 25 is released its spring 30 draws it to position where valve member 28 will fully open port 29, leaving the automatic valve 12 in full control thereof.

The pipe 6 leading to the motor 5, has a valve 32 operated by a rod 33 connected by link 34 to the outer wall of a bellows pneumatic 35 comprising a plurality of bellows elements similar in construction to the bellows pneumatic 13, and connected by tubes 36 to perforations 47 in the tracker board, and by tubes 37 to reservoir 7. A spring 31 is provided for bellows or valve pneumatic 35.

20 The speed may also be controlled by manual means 38 having connection 39 to a valve 40 for control of the suction from the motor 5, this manual control having valve means 41 for disabling the automatic when the manual is in control and a spring 42 for normally moving the manual control to inoperative position, leaving the automatic in control. The expression and speed control valves are inclosed in boxes 50 and 51.

30 The music sheet 43, see Fig. 4, has in addition to the note perforations 44, other perforations 45, for example, near one edge, for controlling expression, and additional perforations 46 which may be near the outer edge, for speed control. No speed or expression marks are needed on the sheet, the speed and expression are determined automatically and without attention of the operator. The sets of holes 45 are, in case a prolonged action is required, each preferably arranged in two rows extending in parallel adjacent lines along the music control sheet, alternating holes overlapping so as to maintain connection with the tracker board perforation (which is widened or split to extend under both rows of holes.) By this means the effect is obtained of a single long hole without unduly weakening the sheet. A similar provision is made on the speed controlling holes.

35 The operation is as follows:—The music sheet being in place and pedals being operated, a condition of suction is produced in the reservoir 7, and the motor 9 is operated thereby to move the sheet forward. The speed controlling holes 46 in the sheet will be arranged to normally admit sufficient air to the valve pneumatic 35 to bring the valve 32 to an intermediate position corresponding to 40 a medium speed of the feeding means. At parts where a slow movement is required, these holes will be diminished to cut off air from the pneumatic which will collapse on account of the continual suction of air therefrom to the reservoir, and the atmospheric

pressure on the outside. Valve 32 is thus drawn over to position to allow less air to pass through it thus decreasing the speed of the pneumatic driving means and slowing up the sheet. When there are no holes 46 passing over the tracker board, the valve 32 will occupy the position for slowest speed. For faster movement the holes 46 are increased and the pneumatic 35 thereby inflated, the spring 31 drawing the valve 32 over to allow more air to be drawn through the pneumatic driving mechanism thereby increasing the speed. Similarly the holes 45 controlling expression will be increased or diminished at different parts of the sheet according to the force of action required at such parts. I have found that when a sharp accentuation of a particular note is desired that it may be secured by providing at that part of the music sheet, holes on all the expression rows or lines, and closing off or leaving blank the corresponding part of the sheet at the tempo side, so as to give a dwell on the note and insuring that the full suction will be developed on the action both by the full spring of the expression valve and by eliminating the waste of suction that normally occurs on driving the motor.

45 While the invention is above described as applied to the piano player, it is obvious that it is equally applicable in connection with any automatic musical instrument operating under the control of the music sheet; for example, self playing pianos, organs, or other musical instruments.

What I claim is:—

1. A piano player comprising, in combination with the tracker board and the action connected thereto, valve means controlling the force of the action and a pneumatic controlling means for said valve means comprising a plurality of elements operative individually and conjointly on said valve means to produce variant movements thereof, a plurality of pneumatic connections from the respective pneumatic elements to the tracker board, and a manual valve for controlling the force of the action, said manual valve being provided with means for disabling the operating means for the pneumatically controlled valve, when the manual valve is in operative position.

2. A piano player comprising, in combination with the tracker board and the action connected thereto, a motor for the music sheet, speed control means therefor comprising a valve and a pneumatic controlling means for said valve consisting of a plurality of elements operative individually and conjointly on said valve to produce variant movements thereof, a plurality of pneumatic connections from the tracker board to the respective pneumatic elements of the speed controlling means, and a manual valve for controlling the speed of the motor, said man-

ual valve being provided with means for disabling the operating means for the pneumatically controlled valve, when the manual valve is in operative position.

5. 3. A piano player comprising, in combination with the tracker board and the action connected thereto, valve means controlling the force of the action and a pneumatic controlling means for said valve means comprising a plurality of elements operative individually and conjointly on said valve means to produce variant movements thereof, a plurality of pneumatic connections from the respective pneumatic elements to the tracker board, and a manual valve for controlling the force of the action, said manual valve being provided with means for cutting off communication through the said controlling pneumatic for the pneumatically controlled valve, when the manual valve is in operative position.

4. A piano player comprising, in combination with the tracker board and the action

connected thereto, a motor for the music sheet, speed control means therefor comprising a valve and a pneumatic controlling means for said valve consisting of a plurality of elements operative individually and conjointly on said valve to produce variant movements thereof, a plurality of pneumatic connections from the tracker board to the respective pneumatic elements of the speed controlling means, and a manual valve for controlling the speed of the motor, said manual valve being provided with means for cutting off communication through the said controlling pneumatic for the pneumatically controlled valve, when the manual valve is in operative position.

In testimony whereof, I have hereunto set my hand at Los Angeles Cal. this 24th day of July 1906.

ROY F. BANCROFT.
